UNITED STATES PATENT OFFICE.

ORRIN B. PECK, OF CHICAGO, ILLINOIS, ASSIGNOR TO MELINDA PECK, OF SAME PLACE.

APPARATUS FOR CENTRIFUGALLY TREATING MOLTEN MATERIAL.

SPECIFICATION forming part of Letters Patent No. 433,145, dated July 29, 1890.

Application filed March 3, 1890. Serial No. 342,440. (No model.)

To all whom it may concern:

Be it known that I, ORRIN B. PECK, a citizen of the United States, residing at Chicago, Illinois, have invented certain new and useful Improvements in Apparatus for Centrifugally Treating Moltten Material, of which the following is a specification.

The object of this invention is to improve a centrifugal apparatus for use in the treatment of molten materials; and it has more particular reference to the construction of the curbing that surrounds the receiving-vessel, and to providing means for protecting its interior.

15 In the drawings, Figure 1 is an elevation, partly in section, of a centrifugal machine embodying my improvements; Fig. 2, a section of Fig. 1 on line 2-2, looking in the direction of the arrows; Fig. 3, an outline view 20 of a portion of the curbing and lining shown in Fig. 2, and Fig. 4 a perspective view of one section of the lining.

V is the receiving-vessel; A, the shaft for supporting and revolving the same; B B, journal-bearings for supporting and maintaining the vertical position of the shaft; E, the curbing surrounding the vessel; F F, plates forming the top and bottom of the curbing; f f, flanges on such plates; G, a plate forming the 25 wall of the curbing; I, a lining or protector for the interior of the curbing; J, a ring or shelf upon which the lining I rests; i, bolts for holding the lining in place; and i' a ring passing around the curbing, through which 30 the bolts i extend.

The receiving-vessel V is surrounded by a strong curbing E, preferably constructed out of two cast-iron or other suitable plates F F, preferably provided with annular flanges f f.

40 These two plates constitute the top and bottom of the curbing, and are preferably held together by means of a sheet of boiler iron or steel riveted or otherwise secured to the flanges f f. In this way the sides or wall of 45 the curbing is preferably as shown in Fig. 1. The curbing serves to catch and confine the material that is treated in the receiving-vessel and discharged from it. The material is 50 discharged or thrown off from the receiving-vessel in a molten condition; but water is

sprayed on it from the pipe h or other convenient means, cooling and hardening it and rendering its action upon the interior of the curbing or wall very severe, rapidly wearing the curbing at the point where it first strikes, 55 and in this way the wall is soon cut or worn entirely through, thus rendering the curbing unfit for further use.

To afford a protector for the interior of the wall of the curbing, and to prevent it from 60 being rapidly destroyed, I have provided a cast-iron or other suitable lining I, preferably made in sections and placed on or over the interior of the wall of the curbing, and located in such a manner that as the material from 65 the receiving-vessel is discharged it will be thrown against the lining instead of the wall proper. In this way it will be seen that the lining I will be worn instead of the wall, and that when the protector or lining is worn so 70 that it is not fit for further use it may be removed and a new one put in its place. I prefer, as above stated, to make this lining in sections, and, as shown in the drawings, I prefer to secure the sections in their place by 75 means of bolts i that extend through the lining and curbing, with their ends carrying the nuts on the outer side of the curbing, so that they are easy of access. I also prefer to provide a ring i' around the outside of the wall 80 of the curbing at any suitable point for the bolts i to pass through. The ring i' is to facilitate the easy locating of the bolts i, since, as I prefer to wrap the outside of the wall between the edges of the flanges f f with wire 85 to secure the required strength, it would be quite a difficult matter to extend the bolts through the wire wrapping if the ring i' was not provided.

To assist in holding the sections of the lining in place, I prefer to provide a ring or shelf J, upon which their lower ends may rest. While I have shown this lining as only covering a portion of the interior of the curbing of course it may be extended down as far as 95 desired; and while I prefer to make it in sections, as shown, which facilitates its easy removal and renewal it may be made in larger pieces, or as will best suit the operator, so long as it is arranged to protect the interior 100

of the curbing; and, as I have also shown, I prefer to make the various sections of the lining so that their edges will lap to prevent the small particles thrown from the receiving-vessel from being driven between the edges of the sections of the lining. This is a matter of choice, and does not very materially effect the utility of the lining; also, as shown in the drawings, I prefer to provide recesses in the inside of the lining at the point where the bolts that hold it in place are located, so that the heads of the bolts may set in them, so to speak, or be countersunk, leaving a comparatively level surface on the interior of the curbing and lining, so the material will not stick.

The lining may be made in various ways and held to place in various ways, as by keys, wedges, or recesses; but as the intention of my invention is to afford a means for protecting the interior of the curbing from severe injury or being rapidly worn out and destroyed by the material discharged from the receiving-vessel, I do not wish to be limited to any particular form of constructing or securing such protector or lining.

I claim—

1. In a centrifugal machine for the treatment of molten material, the combination of a revoluble receiving-vessel adapted to receive the material to be treated, means for supporting and revolving the vessel, a surrounding curbing for arresting the particles thrown off from the receiving-vessel, and a removable lining on the interior of such curbing to prevent it from being rapidly worn out and destroyed by the action of the discharging material from the receiving-vessel, substantially as described.
2. In a centrifugal machine for the treatment of molten material, the combination of a revoluble receiving-vessel adapted to receive the material to be treated, means for supporting and revolving the vessel, a surrounding curbing for arresting the particles thrown off from the receiving-vessel, and a lining composed of removable sections on the interior of such curbing to prevent it from being rapidly worn out and destroyed by the action of the

discharging material from the receiving-vessel, substantially as described.

3. In a centrifugal machine for the treatment of molten material, the combination of a revoluble receiving-vessel adapted to receive the material to be treated, means for supporting and revolving the vessel, a surrounding curbing for arresting the particles thrown off from the receiving-vessel, and a lining composed of removable sections held to place by means of bolts extending through the lining and curbing from the interior to the exterior, substantially as described.

4. In a centrifugal machine for the treatment of molten material, the combination of a revoluble receiving-vessel adapted to receive the material to be treated, means for supporting and revolving the vessel, a surrounding curbing for arresting the particles thrown off from the receiving-vessel, a covering or envelope or wire around the exterior of the curbing, a ring or band around the exterior of the curbing, a removable lining on the interior of the curbing, and bolts to maintain the lining in place, extending through it and the curbing and through the ring on the exterior of the curbing, substantially as described.

5. In a centrifugal machine for the treatment of molten material, the combination of a revoluble receiving-vessel adapted to receive the material to be treated, means for supporting and revolving the vessel, a surrounding curbing for arresting the material thrown off from the receiving-vessel, a removable lining on the interior of such curbing to prevent it from being rapidly worn out and destroyed by the action of the discharging material from the receiving-vessel, having bolts extending through such lining to hold it to place, and the lining having recesses on its interior to accommodate the heads of such bolts, thereby affording a smooth interior surface to the lining, substantially as described.

ORRIN B. PECK.
